GRATE SHAKING AND DUMPING DEVICE

Filed Feb. 23, 1929

UNITED STATES PATENT OFFICE

JAMES MURCHIE, OF TRAVERSE CITY, MICHIGAN, ASSIGNOR TO HOLLAND FURNACE COMPANY, OF HOLLAND, MICHIGAN

GRATE SHAKING AND DUMPING DEVICE

Application filed February 23, 1929. Serial No. 342,073.

This invention relates to improved grate shaking and dumping devices.

The objects of the invention are:

First, to provide an improved construction 5 of shaker.

Second, to provide such a grate shaking and dumping device which avoids the opening of the furnace ash pit during operation.

Third, to provide a grate shaking device 10 with a dumping means that can be operated from the outside of the furnace.

Fourth, to provide an improved shaking lever means.

Fifth, to provide an improved coupling of 15 the shaking means to the grate.

Sixth, to provide improved lever means for dumping the grate.

Objects pertaining to details and economies 20 of construction and operation will definitely appear from the detailed description to follow.

A structure which is a preferred embodiment of the invention is illustrated in the accompanying drawings, in which:

25 Fig. 1 is a front elevation view of the ash pit front of a furnace with my improved grate shaking and dumping means in position, the door of the ash pit being omitted.

Fig. 2 is a plan view of the dumping grate 30 and my improved shaking and dumping means, the ash pit casing of the furnace being omitted.

Fig. 3 is a vertical detail sectional elevation on the irregular line 3—3 of Figs. 1 and 2.

35 Fig. 4 is a detail elevation view of the dumping connection part in elevation similar to Fig. 3, showing the same in dumped position.

Fig. 5 is a detail end elevation view of the shaker lever from the right hand side of Figs. 40 1 and 2.

Fig. 6 is a detail sectional elevation on line 6—6 of Figs. 1 and 2 of the dumping lever.

Fig. 7 is an enlarged detail sectional view 45 through the swivel joint structure taken on line 7—7 of Figs. 1 and 5.

The parts will be identified by their numerals of reference which are the same in all the views.

1 is the ash pit casing of a furnace in the 50 usual form, having the flange doorway or

frame 2. 3 is the dumping grate. 4 is the rocking cross bar on which the grate 3 is pivoted at 5. 6 is the actuating shaker arm secured to the downwardly extending lug 31 on the grate 3 and projecting out to the ash pit 55 door. This arm 6 is oscillated to shake the grate and is dropped down to dump the grate. The same is shown in operative position in Figs. 1, 2 and 3 of the drawing, and in dumped position in Fig. 4.

60 7 is the shaker lever fulcrumed at 71 to the extension of the base bracket 11. 8 is the square reciprocating connecting bar from the lever 7 to shake the grate. It is provided with a swivel connection 81 adapted to play 65 in the vertical slot 72 in the shaker lever 7. The swivel connection 81 is provided with lateral pins 82 engaging in vertical slots 73 on the lever 7, so that the bar 8 which is square can be adjusted to different positions and still 70 be free to reciprocate. This is accomplished by the adjusting lever 9 which is provided with a square hole 91 which engages the reciprocating bar 8. The bar 8 is supported in sleeve 10 carried by bracket 11 and is provided with upwardly extending cheek pieces 12, 13 which embrace the lever 9 and permit 75 it to be rocked through an angle of about 135° to give the bar 8 nearly a half turn. The lever 9 is held in vertical position preferably by 80 suitable stop, and, of course, when the grate is dropped the weight of the grate makes any stop unnecessary.

The inner end of the shaker bar 8 is provided with a U-shaped connection 14 which, 85 with the shaker bar 6, is shown in elevated position so that the center of the U which is offset is above the bar. The sides of the U are recurved as seen in Fig. 3 to engage the sides of the actuating bar 6 during the shaking operation and also to prevent accidental displacement of the slide connection.

Disposed on the bar 6 is the slide connection 15 which has an upwardly projecting ear 151 perforated to pivot upon the central part of the U connection 14. This slide 15 is retained by stop pin 16 from sliding off the end of the bar 6 and is free to move along the bar inside the stop to accommodate the various adjustments and provide a slidable connection to 100

accommodate the oscillations of the shaker bar.

It will be seen that my construction is very simple and very effective. The shaker lever 5 7 is ordinarily manipulated back and forth and shakes the ashes from the grate which is ordinarily all that is required. However, if clinkers accumulate or if for any reason it is desired to dump the grate, it is simply done 10 by manipulating the lever 9, turning the connecting bar 8 through an angle of about 135° which is permitted by the swivel connection to the lever 7. Sufficient rocking motion can be imparted to the dump grate to insure that 15 the whole contents has come down.

The illustration of the grate herein is conventional but will be recognized as the structure of the Holland Furnace Co. which appears in United States Letters Patent No. 20 1,332,353, March 2, 1920. It is therefore not deemed necessary to illustrate it more fully.

I desire to state that my improved grate shaking and dumping device can be greatly modified in its details without departing 25 from my invention. I have shown a swiveled reciprocating bar connection with a swivel connection to the lever. Other means might be provided for permitting the rocking of this bar, it only being necessary to project such a 30 bar far enough through the wall of the furnace to permit of its being manipulated from the outside and still provide for reciprocatory motion. I have provided a very simple connection for the inner end of the bar. This, 35 however, can be greatly modified. The sliding link connection on the rocker bar might be otherwise secured and might even be pivoted in position. I have shown it in a very simple form involving the minimum amount 40 of labor in its production.

Having thus described my invention, what I claim as new and desire to secure by Letters Patent, is:

1. In a grate shaking and dumping device, 45 the combination with the ash pit casing, a dumping grate therein having a shaker arm, of a base bracket outside said casing, a vertically slotted shaking lever fulcrumed thereon, a square reciprocating grate shaker bar, 50 a sleeve for the said shaker bar connected to the side of the ash pit door frame, a swivel block connection for said shaker bar to said shaker lever slidably supported in the slots of the said shaking lever, a dumping lever with 55 square hole engaging said shaker bar for turning it to different angles, transverse cheek pieces supported by said sleeve for receiving the said dumping lever, an offset U-shaped connection at the inner end of said shaker bar 60 with curved end portions for engaging the sides of the shaker arm, a slideable connection on the grate shaker arm with upwardly projecting perforated ear for engaging the central part of the said U-connection whereby 65 the grate can be shaken by the shaker bar and

can be dumped from the outside by rocking said bar and can be restored and held to operative position, as specified.

2. In a grate shaking and dumping device, 70 the combination with the ash pit casing, a dumping grate therein having a shaker arm, of a vertically slotted shaking lever, a square reciprocating grate shaker bar, a swivel block connection for said shaker bar to said shaking lever slidably supported in the slots of the said shaking lever, an adjusting lever with square hole engaging said shaker bar for adjusting it axially to different angles, an offset U-shaped connection at the inner end of said shaker bar with curved end portions 75 for engaging the sides of the shaker arm, a slideable connection on the grate shaker arm with upwardly projecting perforated ear for engaging the central part of the said U-connection, whereby the grate can be shaken by the shaker bar and can be dumped from the outside by rocking said bar and can be restored and held to operative position, as specified.

3. In a grate shaking and dumping device, 80 the combination with the ash pit casing, a dumping grate therein having a shaker arm, of a vertically slotted shaking lever, a reciprocating grate shaker bar, a swivel block connection for said shaker bar to said shaking lever slidably supported in the slots of the said shaking lever, means for adjusting the shaker bar axially to different angles, an offset U-shaped connection at the inner end of said shaker bar with curved end portions 85 for engaging the sides of the shaker arm; a slideable connection on the grate shaker arm with upwardly projecting perforated ear for engaging the central part of the said U-connection, whereby the grate can be shaken by the shaker bar and can be dumped from the outside by rocking said bar and can be restored and held to operative position, as specified.

4. In a grate shaking and dumping device, 90 the combination with the ash pit casing, a dumping grate thereon having a shaker arm, of a vertically slotted shaking lever, a reciprocating grate shaker bar to said shaking lever, a swivel block connection for said shaker bar slidably supported in the slots of the said shaking lever, means for adjusting the shaker bar axially to different angles, an offset pivotal connection at the inner end of said shaker bar, a movable connection on 95 said shaker arm for said pivotal connection whereby the grate can be shaken by the shaker bar or can be dumped from the outside by rocking said bar and can be restored and held to operative position, as specified.

5. In a grate shaking and dumping device, 100 the combination with the ash pit casing, a dumping grate thereon having a shaker arm, of a vertically slotted shaking lever, a square reciprocating grate shaker bar, a sleeve for 105

the said shaker bar connected to the side of the ash pit door frame, a swivel block connection for said shaker bar to said shaking lever slidably supported in the slots of the said shaking lever, dumping lever with square hole engaging said shaker bar for adjusting it axially to different angles, transverse cheek pieces supported by said sleeve for receiving the said dumping lever, an offset pivotal connection at the inner end of said shaker bar, a movable connection on said shaker arm for said pivotal connection whereby the grate can be shaken by the shaker bar or can be dumped from the outside by rocking said bar and can be restored and held to operative position, as specified.

6. In a grate shaking and dumping device, the combination with the ash pit casing, a dumping grate therein having a shaker arm, of a vertically slotted shaking lever, a reciprocating grate shaker bar, a sleeve for the said shaker bar connected to the side of the ash pit doorway, a swivel block connection for said shaker bar to said shaking lever slidably supported in the slots of the said shaking lever, an adjusting lever with hole engaging said shaker bar for adjusting it axially to different angles, transverse cheek pieces supported by said sleeve for receiving the said adjusting lever, an offset pivotal connection at the inner end of said shaker bar, a movable connection on said shaker arm for said pivotal connection whereby the grate can be shaken by the shaker bar or can be dumped from the outside by rocking said bar and can be restored and held to operative position, as specified.

7. In a grate shaking and dumping device, the combination with the ash pit casing, a dumping grate therein having a shaker arm, of a shaker lever fulcrumed at the outside, a reciprocating grate shaking bar, a swivel connection between said bar and the shaker lever, means for adjusting the swivel part of said shaker bar axially, an offset pivotal connection at the inner end of said shaker bar to the grate shaker arm, a movable connection on said shaker arm for said pivotal connection whereby the grate can be shaken by the shaker bar or can be dumped from the outside by rocking said bar and can be restored and held to operative position, as specified.

In witness whereof I have hereunto set my hand.

JAMES MURCHIE.
